UNITED STATES PATENT OFFICE.

MARTIN NEWCOMER, OF PERTH AMBOY, NEW JERSEY, ASSIGNOR TO VOLOTONE COMPANY, OF ELIZABETH, NEW JERSEY, A CORPORATION OF NEW JERSEY.

MACHINE FOR PUNCHING MUSIC-SHEETS.

1,320,643.

Specification of Letters Patent.

Patented Nov. 4, 1919.

Application filed November 27, 1916. Serial No. 133,590.

To all whom it may concern:

Be it known that I, MARTIN NEWCOMER, a citizen of the United States, and residing in the city of Perth Amboy, county of Middlesex, in the State of New Jersey, have invented certain new and useful Improvements in Machines for Punching Music-Sheets, of which the following is a specification, reference being had to the accompanying drawing, forming a part hereof.

The machine which forms the subject of the present invention has been designed with special reference to its use in punching the marginal or side perforations in a music-sheet for the control, through suitable devices in the player piano, of expression, and particularly for the punching of perforations of this character which are not spaced regularly, either in longitudinal or lateral distribution. The mechanism in which the invention is embodied is applicable for other special purposes, and moreover, while reference is made herein to the punching of sheets in the sense of forming perforations therein, it will be obvious that the mechanism is equally applicable to the marking of sheets, by a punch or other suitable marker without actual perforation. It will be understood that the operation of the machine is controlled by a previously punched master sheet and is designed to effect automatically the punching or marking of one or more sheets in exact accordance with the previous punching of the master sheet. The machine will be more fully explained hereinafter with reference to the accompanying drawing in which it is illustrated and in which,—

Figure 1 is a plan view, partly broken out.

Fig. 2 is a view in front elevation, also partly broken out, of a machine which embodies the invention in an improved form.

Fig. 3 is a detail view, partly in elevation and partly in section, and on a larger scale, of the pneumatic devices which operate the punch or marker and control the restarting of the machine after the punching or marking.

Fig. 4 is a detail view in section, on the plane indicated by the line 4—4 of Fig. 3, looking in the direction of the arrows.

Fig. 5 is a similar view of the pneumatic devices which are concerned in moving the punch transversely over the sheet to the predetermined position for punching.

Fig. 6 is a similar view of the pneumatic

devices for controlling the movement of the rolls.

Fig. 7 is a detail view in section, on the plane indicated by the line 7—7 of Fig. 6, looking in the direction of the arrows.

Fig. 8 is a top view of the parts shown in Fig. 5, below the plane indicated by the line 8—8 of Fig. 5.

Fig. 9 is a detail view in section on the plane indicated by the line 9—9 of Fig. 8.

Fig. 10 is a detail view in perspective of a portion of the tracker-bar.

Fig. 11 is a detail view of the pneumatic shown in Fig. 3, in longitudinal section through the valve g^3 .

In order that the relations of the parts may be the more readily understood, it may be stated at the beginning that the master sheet and the sheet or sheets to be perforated or marked are drawn forward in parallel relation, the one over a tracker-bar with pneumatic connections and the other over a dummy tracker-bar or supporting bar under the punch, until a perforation in the master sheet, which is to be reproduced in the other sheets, comes into registration with a slot or port in its tracker-bar. Thereupon movement of both sheets is stopped. The punch is then shifted transversely until it reaches the same relative position with respect to the blank or sheet to the master sheet. Then the punch is operated and the movement of the sheets is recommenced and continued until another perforation in the master sheet comes into registration with the port or slot of its tracker-bar.

The feed-roll a for the perforated master sheet and the feed-roll a' for the sheet or sheets to be perforated, are preferably mounted side by side upon a common axis and upon a common shaft a^2 . A brake a^3 may be applied to one of the rolls, such as the master roll, to prevent overrunning of either roll. The take-up roll a^4 for the master sheet, and the take-up roll a^5 for the sheet or sheets to be perforated, are also mounted preferably on a common axis and on a common sectional shaft a^6 and a' , the two sections being united by a coupling a^8 which permits relative angular adjustment of the two take-up rolls when necessary. The shafts a^2 and a^6 , a' are mounted in suitable bearings a^9 . The shaft a^6 is driven through a friction clutch a^{10} from an alined and longitudinally movable shaft a^{11} which

is acted upon by a spring a^{12} to keep the members of the friction clutch a^{10} normally in contact and may be driven from any suitable source of power through a belt 5 pulley a^{13} .

b is a pneumatic block or casing, which comprises two independent pneumatic devices c and d which are connected, through a common windway b' and a common connection b^2 , with the source of suction of a 10 vacuum creating device, which is not shown and may be of any suitable character. Each of the pneumatic devices c and d may act, through its arm c' or d' , as the case may be, upon a clutch or collar a^{14} , on the shaft a^{11} , to open the clutch a^{10} and therefore stop the movement of the shaft a^6 , a^7 and the master sheet and blank sheet or sheets. The pneumatic devices also perform other functions, as will be described.

As the two pneumatic devices or sets of devices c and d are precisely the same in construction, a description of one, as d , will suffice for both, but before proceeding with 25 the description it may be stated that the tracker-bar e has formed therein a slot or port e' , the ends of which are connected respectively by tubes e^2 and e^3 , with the two pneumatic devices or sets of devices c and d , while the two portions of the slot e' are 30 separated by a movable block or partition e^4 , which is moved automatically, as herein-after explained, to block off any perforation in the master sheet which has been brought into registration with the slot e' . The pneumatic device d has a chamber d^2 to which the tube e^3 from the left hand end 35 of the slot e' in the tracker e is connected, the chamber d^2 being also connected through a port d^8 , normally closed by a spring- 40 pressed valve d^4 and a tube d^5 , with a pneumatic f by which the punch and the movable block or partition e^4 are shifted as herein-after described. The chamber d^2 of the 45 pneumatic d is separated by a diaphragm d^6 from the chamber d^7 which is connected with the windway b' and, through a bleed hole d^8 , with the chamber d^2 or its connecting pipe e^3 . The chamber d^7 is also connected, 50 through a port d^9 , with the chamber d^{10} , which is connected, through a port d^{11} , with the bellows d^{12} of the pneumatic d . The port d^9 is normally closed by a valve d^{13} , the 55 stem of which rests upon the diaphragm d^6 , the valve d^{13} being provided with a bleed hole d^{14} . The chamber d^{10} also communicates through a port d^{14} with the chamber d^{15} , which communicates with the atmosphere. A diaphragm d^{16} separates the chamber d^{15} , 60 from a chamber d^{17} which communicates through a passage d^{18} , with the corresponding chamber c^{17} of the pneumatic c , and a tube d^{19} with a pneumatic device g to be described, the chambers d^{17} and c^{17} being connected in common through the passage d^{18} .

and the tube d^{19} , with the pneumatic device g . The movable member of the bellows d^{12} carries a striker d^{20} which, when the bellows is collapsed, acts upon the stem of the valve d^4 to open the valve and place the chamber 70 and channel d^2 in communication with the tube d^5 . The stem of the valve d^4 works through an air-tight bushing.

The construction of the pneumatic c is the same in all respects as the construction 75 of the pneumatic d , already described, its lower chamber being connected through the tube e^2 with the right hand end of the slot e' in the tracker e and, through a valve indicated by dotted lines at c^4 in Fig. 1, and a 80 tube c^5 , with another part of the pneumatic device f .

The pneumatic device f , as previously stated, accomplishes the lateral shifting of the punch and at the same time the lateral 85 shifting of the movable block e^4 , in one direction or the other, until it blanks the perforations of the master sheet, which may then be in registration with the slot e' of the tracker e . It comprises a bellows f' , the 90 movable member of which has an arm f^2 . The latter is connected by a link f^3 with the slide h which carries the punch and, through an adjustable link f^5 , with the movable block e^4 . The tube d^5 , from the pneumatic device 95 d , is connected to the lower chamber f^3 on one side of the pneumatic device f , the said chamber being separated by a diaphragm f^4 from a chamber f^5 which communicates with the main windway through a tube f^6 . The 100 chamber f^5 is common to both sides of the pneumatic. At one side, the chamber f^5 communicates through a port f^7 with an upper chamber f^8 , which communicates with the atmosphere through a port f^9 . The 105 ports f^7 and f^9 are controlled by a valve f^{10} which may be lifted by the diaphragm f^4 . The chamber f^8 also communicates through a port f^{11} with the bellows members f' , the port f^{11} being closed normally by a spring- 110 pressed valve f^{12} which opens away from the bellows. The tube c^5 , from the pneumatic c , communicates with a chamber f^{13} on the other side of the pneumatic, which chamber f^{13} is separated by a diaphragm f^{14} from the 115 common chamber f^5 . The latter also communicates through a port f^{15} with a chamber f^{16} on the side of the pneumatic corresponding to the tube c^5 . The chamber f^{16} also communicates through a port f^{17} with the atmosphere. A double valve f^{18} , f^{19} , which 120 may be lifted by the diaphragm f^{14} , controls the ports f^{15} and f^{17} . The chamber f^{16} also communicates with the bellows f' through a port f^{20} which is controlled by a 125 flap valve f^{21} opening toward the bellows.

When air at atmospheric pressure is admitted through the right hand portion of the slot e' of the tracker e , the tube e^2 , the valve c^4 and the tube c^5 to the corresponding cham- 130

ber f^{13} , the double valve f^{18}, f^{19} will be lifted, shutting off communication between the chamber f^{16} and the suction chamber f^5 and placing it in communication with the atmosphere, whereby air will be admitted through the flap valve f^{21} to the bellows f' and the latter will be permitted to expand. Through the arm f^2 , the punch slide h and the block e^4 will then be drawn to the right until the perforation of the master sheet which initiated this operation is blanked by the movable block. The punch carrier will then be stopped with its punch in a position which corresponds exactly to that of the perforation in the master sheet which initiated the operation. On the other hand, if air is admitted through a perforation in the master sheet to the left hand portion of the slot e' , that is, to the portion which lies to the left of the movable block e^4 , in whatever position it may be, air at atmospheric pressure will then be admitted through the tube e^3 , the chamber d^2 , the valve d^4 and the tube d^5 , to the chamber f^3 . The diaphragm f^4 will then lift the valve f^{10} to place the chamber f^8 in communication with the suction chamber f^5 and cut off communication between the same and the atmosphere through the port f^9 . As the valve f^{12} opens from the bellows, communication will then be established between the bellows f' and the suction chamber f^5 , and through the arm f^2 and the described connections, the punch carrier h and the movable block e^4 will be moved to the left until the latter blanks the perforation of the master sheet which initiated this particular movement.

The punch carrier h supports a vertically movable punch h' , held normally in its elevated position by a light spring h^2 . It is actuated to punch or mark the paper to be perforated or marked by a hammer h^3 with a head sufficiently broad to accommodate the limited lateral movement of the punch, the hammer being pivoted on a suitable standard h^4 and provided at its rear end with a spring-pressed, pivoted toe h^5 , which permits free movement of the hammer actuator in an upward direction, while providing an operative engagement, when the head of the hammer is to be lifted, by the downward movement of the actuator.

The hammer is actuated by an arm g' which projects from the movable member of a bellows g^2 which forms part of the pneumatic device g , previously referred to. This device not only trips or actuates the hammer, but it restarts the forward movement of the winding-on or take-up rolls which were stopped during the punching operation, through the openings of the clutch a^{10} by the pneumatic devices c or d . The bellows g^2 is collapsed, under the control of an ordinary valve action, sufficiently indicated at g^3 , from the main windway through a tube g^{3x} , being

extended by a spring action as usual. The operation of the valve g^5 , by which the bellows g^2 is placed in communication with the tube g^{3x} , is determined by a channelled g^4 controlled by a valve g^5 which is carried by a pivoted arm g^6 . A small bellows g^7 serves to operate the lever g^6 at the proper time, to lift the valve g^5 , by means of a projecting lip g^8 which engages a long, flat spring g^9 secured at its right hand end near the pivot of the lever g^6 , to the upper surface thereof, so that while the lip g^8 actuates the lever in its downward movement, it is permitted in its upward movement to pass by the end of the spring g^9 , through the upward yielding of the latter. The bellows g^7 , extended by the spring g^{10} , is collapsed by suction in two tubes g^{11} and g^{12} , which are connected respectively to the two ends of the slots e' in the tracker-bar e , which (when covered by the master sheet) is under suction through tubes e^2 and e^3 and the corresponding bleed holes, one of which is shown at d^8 in Fig. 6, from the chamber d^7 . The bellows g^7 carries an arm g^{13} with a valve g^{14} which controls a channel g^{15} . The latter communicates, through the tube d^{19} previously referred to, with the chamber c^{17} of the pneumatic c and, through the channel d^{18} , with the chamber d^{17} of the pneumatic d , so that air is admitted to the chambers c^{17} and d^{17} when the bellows g^7 is extended. A bleed hole g^{16} establishes communication between the channel g^{15} and the main windway through the tube g^{3x} .

It will be understood that when a perforation in a master sheet passes over either end portion of the slot e' of the tracker-bar e air is admitted through the tube e^2 or the tube e^3 under the corresponding diaphragm d^6 and the valve d^{13} is thereby lifted to close the port d^{14} and open the port d^9 , thereby placing the pneumatic d^{12} in connection with the exhaust, whereby, through the arm d' , the clutch a^{10} is opened and the movement of the master sheet and other parts is stopped. Then the valve-block e^4 is moved, together with the punch, until it blanks the perforation in the master sheet. This blanking of the perforation in the master sheet would result in a restarting of the master sheet before the operation of the punch if it were not that devices are provided for the purpose of preventing such restarting by preventing connection of the pneumatic d^{12} with the atmosphere and the consequent expansion of the pneumatic and closing of the clutch. Connection of the pneumatic d^{12} with the atmosphere at d^{15} is prevented by closing the port d^{14} by the valve d^{21} which is carried by the diaphragm d^{16} . The chamber d^{17} above the diaphragm d^{16} is connected, as already described, through the tube d^{19} , with the channel g^{15} previously referred to, so that when the channel g^{15} is opened by the lift-

ing of the valve g^{14} , by the expansion of the small bellows g^7 , air at atmospheric pressure is admitted above the diaphragm d^{16} and the valve d^{20} carried thereby then drops upon 5 the port d^{14} and closes it. The bleed hole d^8 in the valve d^{13} is provided in order that the valve d^{21} carried by the diaphragm d^{16} may be held more closely to its seat by the suction through the bleed hole d^8 in the valve 10 d^{13} so long as the valve d^{13} is held up against the port d^{14} by the diaphragm d^{16} .

At the same time that air is admitted 15 through the perforation in the master sheet and through one end portion or the other of the slot e' in the tracker e , air at atmospheric pressure is also admitted through the tube g^{11} or the tube g^{12} , as the case may be, to the small bellows g^7 , which is thereupon expanded by its spring so as to lift the valve 20 g^{14} from its seat and admit air to the channel g^{15} as already described.

When the perforation in the master sheet is blanked by the movable valve-block e^4 , air at atmospheric pressure is cut off from 25 the bellows g^7 as well as from the chamber below the diaphragm d^6 , and the bellows g^7 will then be collapsed through the tubes g^{11} , g^{12} , the slot e' , the tubes e^2 , e^3 and the bleed holes d^8 .

30 When the bellows g^7 collapse the valve g^{14} , carried by the arm g^{13} of the bellows g^7 is again seated, closing the channel g^{15} , and the chamber d^{17} is then connected with the suction through the tube d^{19} , the bleed hole g^{16} and the tube g^{3x} , whereby the diaphragm d^{16} is lifted and its valve d^{20} is carried away 35 from the port d^{14} , so that air at atmospheric pressure is then admitted to the pneumatic d^{12} which immediately expands and closes 40 the clutch. This action restarts the movement of the master sheet, but not until the hammer has been operated to actuate the punch.

The operation of the machine as a whole 45 has now been sufficiently described and need not be further explained herein.

It will be understood that the essential 50 features of the machine may be embodied in arrangements and combinations other than as shown and described herein and that the invention, except as pointed out in the claims, is not limited to the particular construction, arrangement and combination of parts in which it has been illustrated and 55 described herein as embodied.

I claim as my invention:

1. A machine of the character described, comprising a common shaft and feed rolls for supporting and causing the travel of a 60 master sheet and a blank in parallelism, a punch movable laterally with respect to the blank and means controlled by the master sheet for effecting the lateral movement of the punch.

65 2. A machine of the character described,

comprising means for supporting and causing the travel of a master sheet and a blank in parallelism, a punch movable laterally with respect to the blank, means controlled by the master sheet for effecting the lateral movement of the punch, and means controlled by the master sheet for stopping the movement of the master sheet and the blank. 70

3. A machine of the character described, comprising means for supporting and causing the travel of a master sheet and a blank in parallelism, a punch movable laterally with respect to the blank, means controlled by the master sheet for effecting the lateral movement of the punch, and means controlled by the master sheet for operating the punch. 75

4. A machine of the character described, comprising means for supporting and causing the travel of a master sheet and a blank in parallelism, a punch movable laterally with respect to the blank, means controlled by the master sheet for effecting the lateral movement of the punch, means controlled by the master sheet for stopping the movement 80 of the master sheet and the blank and means controlled by the master sheet for operating the punch when the master sheet and the blank are stationary. 85

5. A machine of the character described, comprising means for supporting and causing the travel of a master sheet and a blank in parallelism, a punch movable laterally with respect to the blank, means controlled by the master sheet for effecting the lateral movement of the punch, means controlled by the master sheet for stopping the movement of the master sheet and the blank, means controlled by the master sheet for operating the punch when the master sheet 90 and the blank are stationary, and means controlled by the operation of the punch and its operating means for restarting the movement of the master sheet and the blank. 95

6. A machine of the character described, comprising means for supporting and causing the travel of a perforated master sheet, including a clutch, pneumatic means to operate the clutch, pneumatic devices controlled by the master sheet to initiate the operation of the clutch-operating means to open the clutch, and independent pneumatic devices to initiate the operation of the clutch to close the same. 110

7. A machine of the character described, comprising means for supporting and causing the travel of a perforated master sheet, including a clutch, two sets of means to operate the clutch, and two sets of devices controlled by the master sheet to initiate 115 severally the operation of the corresponding clutch-operating means to open the clutch, and a single independent set of devices to initiate the operation of the clutch-operating means to close the clutch. 120

8. A machine of the character described, comprising a tracker-bar having a recess or chamber in its surface, a valve-block movable longitudinally in said recess or chamber, means for causing the travel of a master sheet over the tracker-bar, including a clutch, two sets of pneumatic devices to operate the clutch, two sets of devices to initiate respectively the operation of the corresponding clutch-operating means, and pneumatic connections from the ends of said recess or chamber to said sets of independent devices respectively.

9. A machine of the character described, comprising a tracker-bar having a recess or chamber in its surface, a valve-block movable longitudinally in said recess or chamber, means for causing the travel of the master sheet over the tracker-bar, including a clutch, two sets of devices to initiate the operation of the clutch-operating means to open the clutch, pneumatic connections from the ends of said recess or chamber to said sets of devices respectively, and independent pneumatic devices to initiate the operation of the clutch-operating means to close the clutch.

10. A machine of the character described, comprising means for supporting and causing the travel of a perforated master sheet and a blank in parallelism, including a clutch, means to operate the clutch, devices controlled by the master sheet to initiate the operation of the clutch-operating means to open the clutch, a punch, means controlled by the master sheet for operating the punch when the master sheet and the blank are stationary, and means controlled by the operation of the punch for initiating the operation of the clutch-operating means to close the clutch.

11. A machine of the character described, comprising means for supporting and causing the travel of a master sheet and a blank in parallelism, including a clutch, pneumatic means to operate the clutch, pneumatic devices controlled by the master sheet to initiate the operation of the clutch-operating means to open the clutch, a punch, pneumatic means for operating the punch when the master sheet and the blank are stationary, and pneumatic devices controlled by the operation of the punch to initiate the operation of the clutch-operating means to close the clutch.

12. A machine of the character described, comprising means for supporting and causing the travel of a master sheet and a blank in parallelism, a tracker-bar having a longitudinal recess or chamber in the surface thereof, a valve-block movable longitudinally in said recess or chamber, a punch movable laterally with respect to the blank, pneumatic means to shift the valve-block and the punch laterally, and pneumatic de-

vices connected to the recess or chamber in the tracker-bar to initiate and control the operation of said shifting means.

13. A machine of the character described, comprising means for supporting and causing the travel of a perforated master sheet and a blank in parallelism, a tracker-bar having a longitudinal recess or chamber in the surface, a valve-block movable longitudinally in said recess or chamber, a punch movable laterally with respect to the blank, pneumatic means to shift the valve-block and punch laterally, two sets of pneumatic devices to initiate the operation of said shifting means in opposite directions respectively, and pneumatic connections from the ends of said recess or chamber to said pneumatic devices respectively.

14. A machine of the character described, comprising means for supporting and causing the travel of a perforated master sheet and a blank in parallelism, including a clutch, pneumatic means to operate the clutch, a punch, pneumatic means to operate the punch, and pneumatic devices controlled by the clutch opening movement of the clutch-operating means to initiate the operation of the punch-operating means.

15. A machine of the character described, comprising means for supporting and causing the travel of a perforated master sheet and a blank in parallelism, including a clutch, pneumatic means to operate the clutch, a punch, pneumatic means to operate the punch, and pneumatic devices controlled by the operation of the punch-operating means to initiate the operation of the clutch-operating means to close the clutch.

16. A machine of the character described, comprising means for supporting and causing the travel of a perforated master sheet and a blank in parallelism, including a clutch, pneumatic means to operate the clutch, a punch, pneumatic means to operate the punch, pneumatic devices controlled by the clutch opening movement of the clutch operating means to initiate the operation of the punch-operating means, and pneumatic devices controlled by the operation of the punch operating means to initiate the operation of the clutch-operating means to close the clutch.

17. A machine of the character described, comprising means for supporting and causing the travel of a sheet to be perforated, including a clutch, a bellows in operative relation with the clutch, pneumatic devices to control the operation of the bellows, a punch movable laterally with respect to the sheet, a bellows to shift the punch, pneumatic devices to control the operation of the punch-shifting bellows including a controlling valve, and means operated by the clutch-controlling bellows to control said valve.

18. A machine of the character described,

comprising means for supporting and causing the travel of a sheet, including a clutch, two bellows in operative relation with said clutch, and independent sets of pneumatic devices for controlling the operation of said bellows respectively to open or close the clutch.

19. A machine of the character described, comprising means for supporting and causing the travel of a sheet to be perforated, a punch movable laterally with respect to the sheet, a bellows in operative relation with the punch, a connection to an exhaust system, and pneumatic devices to place the bellows in communication with the atmosphere or the exhaust system to cause the punch to be moved in one direction or the other.

20. A machine of the character described, comprising means for supporting and causing the travel of a master sheet and a blank in parallelism, a tracker-bar having a chamber or recess in its surface, a valve-block movable longitudinally in said chamber or recess, a punch movable laterally with respect to the blank, a connection between the valve-block and the punch whereby they move together, a bellows in operative relation with the punch and valve-block to shift the same, a connection to an exhaust system, pneumatic devices to place said bellows in communication with the atmosphere or with the exhaust system, and pneu-

matic connections from said chamber or recess to said devices to control the action thereof.

21. A machine of the character described, comprising a punch, a hammer to actuate the same, a bellows to actuate the hammer, a connection to an exhaust system, pneumatic devices to place the bellows in communication with the atmosphere or the exhaust system, a valve to control the bellows, a valve-carrying lever, a bellows to actuate said lever, and pneumatic devices to control the last named bellows.

22. A machine of the character described, comprising a punch, a hammer to actuate the same, a bellows to actuate the hammer, a connection to an exhaust system, pneumatic devices to place the bellows in communication with the atmosphere or the exhaust system, a valve to control the bellows, a valve-carrying lever, a bellows to actuate said lever, a spring mounted on the lever and adapted to permit the bellows to move in one direction without operation of the lever and to insure operation of the lever through movement in the opposite direction, and pneumatic devices to control the last named bellows.

This specification signed this 24th day of November A. D. 1916.

MARTIN NEWCOMER.
